UNITED STATES PATENT OFFICE.

ROBERT A. ROBERTSON, OF LOCKHART, TEXAS.

WATER MOTOR.

Application filed December 15, 1924. Serial No. 756,023.

To all whom it may concern:

Be it known that I, ROBERT A. ROBERTSON, a citizen of the United States, residing at Lockhart, in the county of Caldwell and 5 State of Texas, have invented a new and useful Water Motor, of which the following is a specification.

This invention relates to water motors of the type commonly known as current 10 motors.

The primary object of the invention is to provide a motor of this character which may be elevated or lowered at the will of the operator to adapt the device for use under 15 various conditions and to regulate the speed of the motor.

A further object of the invention is to provide a device of this character wherein the supporting shaft will be held against 20 lateral movement at all times regardless of the water and wind pressure directed thereto.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed, may be made within the scope of what is claimed, without departing from the spirit of the invention.

Referring to the drawings:

Figure 1 is a plan view of a current motor 35 constructed in accordance with the invention.

Figure 2 is a side elevational view thereof, parts of the frame being shown in section.

Figure 3 is a sectional view taken on line 40 3-3 of Figure 2.

Figure 4 is a sectional view taken on line 4-4 of Figure 2.

Figure 5 is a fragmental detail view illustrating a modified form of elevating 45 means.

Figure 6 is a sectional view taken on line 6-6 of Figure 5.

Referring to the drawings in detail, the 50 reference character 5 indicates the base or foundation on which the motor is supported, the same being shown as constructed preferably of concrete, but it is to be understood that any suitable foundation may be employed as a support.

Extending from the foundation 5 are vertical supports 6 which are braced and held in

their upright positions by means of the brace rods 7. These vertical supports 6 are formed with longitudinal slots extending from points substantially intermediate their ends to the upper extremities thereof, which slots provide guideways for the bearings 8 which are formed with lateral grooves 9 to permit of vertical movement of the bearings 8 within the slots.

Mounted within the bearings 8 is the main supporting shaft 10 on which the wheel indicated at 11 is mounted, the wheel being secured to the shaft 10 to cause the shaft 10 to rotate when the wheel is rotated. At one 70 end of the shaft 10 is a universal joint 12 which provides means for connecting the driven shaft 13 to the shaft 10, the universal joint allowing for vertical movement of the shaft 10 while the shaft is rotating.

Mounted on the base 5 are cylinders 14 that are provided with open upper ends, the cylinders accommodating the floats 15 which are preferably hollow providing air chambers. Secured to the floats 15 are vertical 80 arms 16 that are provided with bearing members 17 which connect the arms 16 to the shaft 10, in a manner to permit of rotary movement of the shaft 10 within the bearings 17.

Openings 17' are formed in the walls of the cylinders 14 and disposed at points below the normal level of the water in which the motor operates. A valve member 18' is arranged adjacent to each opening 17' so 90 that the openings of the cylinders may be closed at the will of the operator. In operation, the openings permit water to enter the cylinders 14 to cause the floats 15 to rise and fall as the water level in the stream in which 95 the motor operates rises.

Communicating with the cylinders 14 through the pipes 19 is a feed pipe 19 which is designed to permit water to be forced into the cylinders 14 to cause the floats to rise in 100 their cylinders, should it be desired to elevate the wheel 11 to facilitate repairing thereof. When water is to be forced through the pipe 19 and into the cylinders 14 the valve members 18' are operated to close the 105 openings 17' and prevent the water forced into the cylinders from passing out through the openings.

The wheel 11 includes lateral disks 20, which disks are connected by means of the 110 curved blades 21 which are curved in such a way as to catch the water, the blades form-

ing pockets for this purpose. Thus it will be seen that when a device of this character is positioned in a stream, the water will impinge on the blades to rotate the shaft 10, so that power may be taken therefrom.

It will be obvious that should the stream rise in the event of floods or the like, the wheel will be automatically elevated to the end that the wheel will be relieved of undue strain which would tend to damage the structure.

In the modified form of the invention as illustrated by Figure 5 of the drawings, the wheel is indicated at 22 and is shown as secured to the shaft 23 which has its ends positioned to operate in the bearings 24 that move in suitable cut out portions formed in the uprights 25. In this form of the invention, the bearing members 24 are provided with threaded openings to accommodate the screws 26 that have their upper ends mounted in suitable openings at the upper ends of the uprights 25. Mounted at the upper end of the screws 26 are pinions 27 that engage pinions 28 of the shaft 29 which is provided with suitable means whereby the shaft 29 may be manually rotated. Thus it will be seen that due to this construction, rotation of

the shaft 29 will operate to raise or lower the bearings 24 and adjust the wheel 22 with respect to the water surface.

I claim:—

In a device of the character described, a base, uprights on the base, vertically movable bearing members mounted on the uprights, a shaft having its ends positioned within the bearing members, a wheel mounted on the shaft to rotate therewith, vertical cylinders supported on the base, said cylinders having openings arranged at points intermediate their ends, valve members for controlling the passage of fluid through the openings, a pipe for admitting fluid to the lower ends of the cylinders, floats in the cylinders, arms mounted on the shaft and having connection with the floats for moving the shaft and wheel supported thereby when water is admitted to the cylinders.

In testimony that I claim the foregoing as my own, I have hereto affixed my signature in the presence of two witnesses.

ROBERT A. ROBERTSON.
